UNITED STATES PATENT OFFICE

119,667

DESIGN FOR A DRESS ENSEMBLE

Elsye Kay, New York, N. Y.

Application January 27, 1940, Serial No. 89,756

Term of patent 3½ years

To all whom it may concern:

Be it known that I, Elsy Kay, a citizen of the United States of America, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a front view of the dress member of the ensemble.

Fig. 4 is a rear view of Fig. 3.

The characteristic feature of my design resides in the combination on the ensemble disclosed of the specific dress section having a tapered, contrastingly trimmed, neckline which is shaped as shown in association with the specific redingote member having wide contrasting lapels which match the neckline trim of the dress.

I claim:

The ornamental design for a dress ensemble, substantially as shown and described.

ELSYE KAY.
